C. L. LILLEBERG

SWITCHING DEVICE

Filed April 23, 1919

Inventor:
Charles L. Lilleberg
By G. L. Gray
Atty.

UNITED STATES PATENT OFFICE.

CHARLES L. LILLEBERG, OF CHICAGO, ILLINOIS.

SWITCHING DEVICE.

Application filed April 23, 1919. Serial No. 292,112.

To all whom it may concern:

Be it known that I, CHARLES L. LILLEBERG, citizen of the United States, residing at Chicago, in the county of Cook and State of Illinois, have invented a certain new and useful Improvement in Switching Devices, of which the following is a full, clear, concise, and exact description.

My invention relates to switching devices and is of particular service where employed in the construction of timers for controlling the occurrence of the ignition sparks that fire the charges in internal combustion engines. The invention, however, is not to be limited to any particular use to which the switch is adapted.

The switching device of my invention includes relatively rotatable contact members each in the form of an arm whose base portion is transverse to the axis of rotation of the rotatable contacting member and whose contacting portion is angular to its base portion, the contacting portions of the contacting members extending toward each other. One of these contacting members is preferably in the form of a bifurcated spring arm whose base portion is transverse to the axis of rotation of the rotatable contacting member and having two contact parts angular to said base portion and located nearer said axis of rotation than said base portion. The other contacting member is preferably in the form of a rigid arm having a base portion transverse to said axis of rotation and extending from such axis toward the other contacting member, this rigid arm including a contact portion angular to its base portion and receivable between the contacting parts upon the two part contacting member, the contacting portions upon the two contacting members extending toward each other.

I will explain my invention more fully by reference to the accompanying drawing showing the preferred embodiment thereof and in which Fig. 1 is a sectional view on line 1—1 of Fig. 2; Fig. 2 is a sectional view on line 2—2 of Fig. 1; Fig. 3 is a perspective view illustrating the rigid contact arm structure; Fig. 4 is a view of a sheet metal blank from which the structure of Fig. 3 may be formed; Fig. 5 is a perspective view of the spring contact arm structure and the mounting therefor; and

Fig. 6 is a view of a blank out of which the 55 spring arm of Fig. 5 may be formed.

Like parts are indicated by similar characters of reference throughout the different figures.

In the embodiment of the invention shown 60 the rigid contacting member is the rotatable member, being mounted upon an engine driven shaft 1 when the structure is employed as a timing switch. This rigid contacting member may include a sleeve 2 65 which is rigidly secured to the engine driven shaft 1, there being a key slot 3 in the sleeve 2 for receiving a key 4 upon the shaft. An arm is rigidly connected with the sleeve 2, the base portion 5 of this arm branching 70 from one end of the sleeve to be transverse to the axis of rotation of the shaft 1 and the contacting arm carried thereby. The contacting arm also includes a contacting portion 6 which is angular to its base portion 75 and is desirably of the form illustrated clearly in Figs. 1, 2 and 3. The rigid contact arm structure may be formed out of a sheet of metal having the contour illustrated in Fig. 4. The sheet of metal is provided with a mortise formation 7 at one end and a tenon formation 8 at an opposite end and a branch 9 extends from a side of the sheet. The blank may be curled into a cylindrical shell, the tenon 8 meshing with the mortise 85 7. The inner portion of the branch 9, that which is to constitute the base 5 of the rigid arm, is bent at right angles to the sleeve and the outer portion is bent at right angles to the inner portion to form the contacting 90 part 6.

Suitable die mechanism is employed to form the blank into the complete structure shown in Fig. 3 and in the forming operation the contacting portion 6 is beveled along 95 its bottom and side edges to enable said contacting portion 6 gradually to enter into engagement with and become separated from the complementary contact portion.

There are a number of complementary contacting members, one for each spark plug in the engine, although I do not limit myself to the number of such complementary contacting members, particularly where the switching device is useful for other purposes. 100 105

These complementary contacting members are desirably each in the form of a two part spring arm formed from the single blank

illustrated in Fig. 6 which is folded into the form illustrated in Figs. 1, 2 and 5. The base portion 5' of each spring contacting member is transverse to the axis of rotation 5 of the rotatable contacting member 5-6 and is secured at its outer end to a shell 10 that encloses the structure. A binding post or screw 11 passes through the outer base portion of each spring contacting member 19 and through a block of insulation 12 and a washer of insulation 13. A nut 14 is placed upon the outer end of each screw 11 and serves to assemble the spring contact arms and shell. Each screw 11 also carries another nut 15 which serves to clamp a conducting wire 16 against the nut 14, the nut 15 thus also serving as a locking nut. For ease of assembly the interior of the housing 10 is provided with a pocket 17 for each insulating block 12. Opposite walls of these pockets slope toward each other, the block 12 having corresponding sloping sides whereby the block may be quickly positioned within the housing, each screw 11 and the inner neck portion of the washer 13 also serving quickly to define the location of each block with respect to said housing.

The extreme outer end of each spring contacting member is in the form of a tail 18 receivable in a notch 19 in the corresponding mounting block 12. By this construction the position of the spring contacting arm with respect to its mounting block 12 is fixedly defined and as the position of said mounting block with respect to the housing 10 is fixedly defined the transverse position of the spring contacting arm with respect to the axis of rotation of the rotatable contacting member 5-6 is assured. The inner ends of the two parts of each spring contacting member carry two contacting parts 20 and 21 which are angular to the base portion of such spring contacting member. The contacting portion 20, 21 upon each spring contacting arm and the contacting portion 6 upon the rigid contacting arm extend toward each other. The contacting portion 6 is receivable between the contacting parts 20 and 21 in either direction of rotation of the shaft 1.

The base portion 5' of each spring contacting member, extending angularly to the axis of rotation of the contacting member 5-6, and being further removed from said axis than are the contacting parts 20, 21, positions these parts at the circle of rotation of the contacting portion 6, the contacting part 21 being upon the outer side of this circle and therefore engageable with the outer surface of the contacting portion 6 and the contacting part 20 being upon the inner side of this circle and therefore engageable with the inner surface of the contacting portion 6. The contacting parts 20 and 21, which are angular to the base portion 5'

of each spring contacting member, are preferably substantially parallel with the axis of rotation of the contacting member 5-6 and the contacting portion 6 is also substantially parallel with the axis of rotation of the contacting member 5-6. A gap is desirably preserved between the contacting parts 20, 21 by a finger 22 upon one of these parts that engages the other part but this finger allows the parts 20 and 21 normally to be close enough together to enable the contacting portion 6 to spread them apart as it passes therethrough in order to make good rubbing contact therebetween. By this arrangement the contacting portion 6 does not have undue spreading action upon the contacting parts 20 and 21 but just enough to maintain the desired degree of rubbing contact. By bringing the contact parts 20 and 21 nearer to the axis of rotation of the contacting member 5-6 than is the base portion 5' which supports the contacting parts 20 and 21, the circle of rotation of the contacting member 5-6 and the circle containing the contacting parts 20 and 21 is materially reduced in radius to reduce the rate of travel of the contacting portion 6 over the contacting parts 20 and 21, thereby reducing the wear upon these co-operating switch parts.

By the construction exhibited the base portion 5' of each spring contacting member is not in the plane of rotation of the contacting portion 6 at the circle of rotation of this contacting portion but all of said parts 6, 20 and 21 are in the same plane whereby the contacting portion 6 passes over the base portion 5' of each spring contacting member irrespective of the direction of rotation of the contacting portion 6. Likewise the base portion 5 of the contacting member 5-6 is outside of the plane of movement of the contacting portion 6. The contacting parts 20 and 21 extend toward the contacting portion 6 but not far enough to engage the base portion 5 and likewise the contacting portion 6 extends toward the contacting parts 20 and 21 but not far enough to engage the base portion 5'. Thus while the contacting parts 6, 20 and 21 are in the same circle neither of these parts can engage the base portion carrying the other.

This arrangement permits the shaft 1 carrying the contact 6 to shift longitudinally of its axis without interfering with the engagement of this contact with its complementary contacts 20 and 21. This has been a serious difficulty in the making of timing switches for gas engines where the contacting parts do not extend angularly to the plane of rotation of the rotatable contacting member and are not supported upon base portions which are clear of this plane of rotation at the circle of rotation of the rotatable contacting member.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

10 1. An electrical switching device comprising relatively rotatable members one within the other, arms projecting respectively from the interior and exterior of said members with their free ends spaced longitudinally 15 of the members, and a lateral extension on the free end of each arm directed toward the other arm, said extensions forming cooperating contacts.

20 2. An electrical switching device comprising relatively rotatable members one within the other, arms projecting respectively from the interior and exterior of said members with their free ends spaced longitudinally 25 of the members, and a lateral extension on the free end of each arm directed toward the other arm, said extensions forming cooperating contacts whose effective contacting surfaces are disposed entirely between the free ends of said arms.

30 3. An electrical switching device comprising relatively rotatable members one within the other, contact supports projecting respectively from the interior and exterior of 35 said members with their free ends spaced longitudinally of the members, one of said supports comprising contiguous spring arms each having a lateral extension on its free end directed toward the other support and forming separable spring contacts, and a 40 lateral extension on the free end of the other support directed toward the first named support and forming a contact receivable between the first named contacts.

45 4. An electrical switching device comprising relatively rotatable members one within the other, contact supports projecting respectively from the interior and exterior of 50 said members with their free ends spaced longitudinally of the members, one of said supports comprising contiguous spring arms each having a lateral extension on its free end directed toward the other support and forming separable spring contacts, and a 55 lateral extension on the free end of the other support directed toward the first named support and forming a contact receivable between the first named contacts, the effective engaging surfaces of said contact being disposed entirely between the 60 free ends of said supports.

5. An electrical switching device comprising relatively rotatable members one within the other, contact supports projecting respectively from the interior and exterior of 65 said members with their free ends spaced

longitudinally of the members, one of said supports comprising contiguous spring arms each having a lateral extension on its free end directed toward the other support and forming separable spring contacts, means 70 normally holding said arms in predetermined separation at their free ends, and a lateral extension on the free end of the other support directed toward the first named support and forming a contact receivable between the first named contacts. 75

6. An electrical switching device comprising relatively rotatable members one within the other, contact supports projecting respectively from the interior and exterior of 80 said members with their free ends spaced longitudinally of the members, one of said supports comprising contiguous spring arms each having a lateral extension on its free end directed toward the other support and forming separable spring contacts, means carried by one of said arms normally holding the arms in predetermined separation at their free ends, and a lateral extension 85 on the free end of the other support directed toward the first named support and forming a contact receivable between the first named contacts. 90

7. An electrical switching device including relatively rotatable contacting members 95 each in the form of an arm having a base portion and a contacting portion angular to the base portion, the contacting portion upon each relatively rotatable contacting member extending toward the base portion of the other relatively rotatable contacting member, the base portions of said relatively 100 rotatable contacting members being outside the plane of rotation of the contacting portion of the rotatable contacting member at the circle of rotation of this contacting portion whereby said base portions are not engaged by said contacting portions, the contacting portion of the relatively rotatable contacting members being in the form 105 of a two part spring that receives the contacting portion of the rotatable contacting member therebetween, one part of said two part spring carrying a finger which engages the complementary part and normally maintains a gap between said two parts. 110

8. An electrical switching device including relatively rotatable contacting members each in the form of an arm having a base portion and a contacting portion angular to the base portion, the contacting portion upon each relatively rotatable contacting member extending toward the base portion of the other relatively rotatable contacting member, the base portions of said relatively 115 rotatable contacting members being outside the plane of rotation of the contacting portion of the rotatable contacting member at the circle of rotation of this contacting portion whereby said base portions are not en- 120

gaged by said contacting portions, the contacting portion of the relatively rotatable contacting members being in the form of a two part spring that receives the contacting

5 portion of the rotatable contacting member therebetween, one part of said two part

complemental part and normally maintains a gap between said two parts, said other contacting member being substantially rigid throughout.

In witness whereof, I hereunto subscribe my name this 18th day of April, A. D., 1919.

CHARLES L. LILLEBERG.
